UNITED STATES PATENT OFFICE

2,415,895

MANUFACTURE OF GASEOUS DISCHARGE TUBES

Francisce Gonzalez Lopez, Buenos Aires, Argentina, assignor, by mesne assignments, to General Electric Company, Schenectady, N. Y., a corporation of New York

Application June 17, 1944, Serial No. 540,770

4 Claims. (Cl. 316—14)

1

This invention relates to electric discharge tubes comprising a mercury vapour filling and more particularly to a means for dosing the mercury filling within these tubes.

In the prior art of manufacturing electric discharge tubes it has been known to inject a drop of mercury into the tube during or after evacuation. However, this method entails serious drawbacks inasmuch as a special injecting machinery is required and the injected mercury drop may sometimes damage the layer of fluorescent material coated on the interior surface of the tube envelope.

In order to obviate the above difficulties it has been suggested by J. L. Cox in his U. S. Patent No. 2,283,189 to enclose the quantity of mercury required for the correct operation of the discharge tube in a roughly sealed metal container or "bomb" and to mount this container in heat-receiving relationship with respect to one of the filamentary electrodes of the tube. By heating the filament to a convenient temperature the metal containers or "bombs" are exploded and the enclosed mercury is liberated and penetrates into the tube envelope.

But, as already explained hereinabove, the metal containers are only roughly sealed so that during exhaustion mercury vapours may escape and penetrate into the vacuum pumping system unless precautions are taken by inserting mercury traps at adequate points of the exhausting system. Furthermore, the filament used for exploding the metal container has to be overdimensioned in order to withstand the passage of the current necessary for generating the high temperature required.

I have now found that the difficulties referred to above are avoided in a simple manner by making use of an evacuated and hermetically sealed glass ampule enclosing the required quantity of mercury and placed in a metal casing closed by a metal gauze. The metal casing is supported by one of the lead-in wires of the discharge electrode of the tubes and the mercury is liberated by subjecting the casing to a high-frequency field of considerable intensity so that the ampule cracks open due to the heat generated by the currents induced in the casing.

In the present invention I retain all the advantages deriving from the utilization of the roughly sealed metal container disclosed in the above-mentioned patent and in addition provide a means whereby discharge electrodes having normal filaments may be used. Furthermore, since the mercury is enclosed in an evacuated and

2

hermetically sealed container, the exhaustion of the tube can be carried out as if no mercury were present and the final degree of vacuum obtained will not be substantially altered after the liberation of the mercury, since the dosing ampule has been evacuated to the same degree of vacuum as the discharge tube.

The main object of my invention is to provide an improved means for dosing the mercury vapour filling within electric discharge tubes in a more accurate and simpler way than has been the case heretofore.

This and further objects and advantages of my invention will become apparent from the consideration of the following detailed description taken in connection with the accompanying drawing which forms part of the specification and in which:

Fig. 1 is an enlarged longitudinal sectional view 20 through the metal casing containing the glass ampule made in accordance with this invention.

Fig. 2 is a cross section taken on the lines 2—2 indicated in Fig. 1.

Fig. 3 illustrates a longitudinal section of an 25 electric discharge tube envelope including the mercury vapour dosing means according to the present invention; and finally

Fig. 4 is a lateral view of the portion of the 30 tube envelope including the dosing ampule according to the present invention.

Referring now to the drawing, wherein the same reference characters indicate like or corresponding parts or elements, it can be seen that the dosing means according to the present invention comprises an evacuated and hermetically sealed glass ampule 10 enclosing a small quantity of mercury 11 and placed in a metal casing 12 which is closed by means of a nickel gauze cover 13. A wire 14 welded to metal casing 12 and to one of the lead-in wires 15 of the discharge electrode 16, supports the dosing ampule 10 and casing 12 within glass envelope 17 of the electric discharge tubes. Discharge electrode 16 and opposite electrode 16' are formed of a coil-coiled filament 18 conductively connected to and supported by lead-in wires 15, each of which is provided with a starting electrode constituted of a wire 19 welded to the corresponding lead-in wire and extending parallel to and on opposite sides of filament 18. Metal casing 12 is located within envelope 17 so that it does not interfere with the normal operation of the discharge electrode 16 by which it is supported.

Envelope 17 may be subjected to the normal processing steps required in the manufacture

of electric discharge tubes, the mercury filling of the tube being enclosed in the hermetically sealed dosing ampule 10. During or after the last processing step the extreme end of envelope 17 containing dosing ampule 10 is introduced in a high-frequency field generated within a coil 20 connected to a high-frequency generator 21 and metal casing 12 is heated to relatively high temperature by the eddy currents induced therein, the generated temperature causing dosing ampule 10 to crack open and to liberate the enclosed mercury 11 which penetrates into the interior of glass envelope 17 through the orifices 13' of cover 13.

The cracking of dosing ampule 10 may be facilitated by marking the outer surface thereof with a diamond cutter, as indicated with lines 22 in the drawing of Fig. 1.

The high-frequency field to which the metal casing with dosing ampule 10 is subjected is normally adjusted to a value at which only small cracks in ampule 10 will be produced. However, this adjustment is not critical and even an intensity causing dosing ampule 10 to break into two or more parts can be used, since these parts will be held together by metal casing 12 and cover 13 and will not penetrate into the interior of envelope 17.

It will be appreciated that modifications of the disclosed embodiment of my invention are possible without departing from the spirit of my invention or the scope of the appended claims.

I claim:

1. In an electric discharge tube comprising a hermetically sealed envelope containing discharge electrodes, a source of mercury in said envelope comprising an evacuated and hermetically sealed glass ampule containing a quantity of mercury, a metal casing enclosing said ampule and having a perforated wall whereby heating of said casing will cause said ampule to be fractured to liberate the mercury, and means to support said casing within said envelope.

2. In an electric discharge tube comprising a hermetically sealed evacuated envelope contain-

ing discharge electrodes, a source of mercury in said envelope comprising a hermetically sealed glass ampule containing a quantity of mercury and evacuated to the same degree as said envelope, a metal casing enclosing said ampule and having a perforated wall whereby heating of said casing will cause said ampule to be fractured to liberate the mercury, and means to support said casing within said envelope.

3. In an electric discharge tube comprising a hermetically sealed envelope containing discharge electrodes, a source of mercury in said envelope comprising an evacuated and hermetically sealed glass ampule containing a quantity of mercury, a sheet metal casing enclosing said ampule and having an open side covered by a metal gauze whereby heating of said casing will cause said ampule to be fractured to liberate the mercury, and means to support said casing within said envelope.

4. In an electric discharge tube comprising an elongated hermetically sealed envelope containing discharge electrodes at its ends, a source of mercury in said envelope comprising an evacuated and hermetically sealed glass ampule containing a quantity of mercury, a metal casing enclosing said ampule and having a perforated wall whereby heating of said casing will cause said ampule to be fractured to liberate the mercury, and means to support said casing within said envelope adjacent to one end wall of said envelope and with its perforated wall facing said envelope end wall.
